CLAIM

The ornamental design for a shaving razor stand, as shown and described.

DESCRIPTION

FIG. 1 is a perspective view of a shaving razor stand showing our new design;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

The broken lines shown illustrate portions of the shaving razor stand and form no part of the claimed design.
